[57] CLAIM

The ornamental design for a transom shroud for the rear
end of a boat, as shown and described.

DESCRIPTION

FIG. 1 is a perspective view of a transom for the rear
end of a boat shroud showing our new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a side elevational view thereof, the opposite
side comprising a mirror image thereof;
FIG. 7 is a sectional view taken generally along line
7—7 of FIG. 2 in the direction of the arrows;
FIG. 8 is a sectional view taken generally along line
8—8 of FIG. 2 in the direction of the arrows; and,
FIG. 9 is a sectional view taken generally along line
9—9 of FIG. 2 in the direction of the arrows.

FIG. 1
